CLAIM

An ornamental design for a cover for a linear shower drain, as shown and described.

DESCRIPTION

FIG. 1 is a top plan view of a cover for a linear shower drain according to the present invention.

FIG. 2 is a bottom plan view of the cover for a linear shower drain of FIG. 1.

FIG. 3 is a front elevational view of the cover for a linear shower drain of FIG. 1. The rear of the cover for a linear shower drain has the same appearance like the front of the cover for a linear shower drain.

FIG. 4 is a left side elevational view of the cover for a linear shower drain of FIG. 1. The right side of the cover for a linear shower drain has the same appearance like the left side of the cover for a linear shower drain.

FIG. 5 is a perspective view of the cover for a linear shower drain of FIG. 1.

FIG. 6 is a perspective view of the cover for a linear shower drain of FIG. 1 showing a partial cross-section of the cover; and,

FIG. 7 is an exploded perspective view of the cover for a linear shower drain of FIG. 1.
